DESIGN FOR A VAGINAL DIAPHRAGM INSERTER

Otto L. Schmitt, Denver, Colo.

Application April 24, 1945, Serial No. 119,166

Term of patent 14 years

(Cl. D83—1)

To all whom it may concern:

Be it known that I, Otto L. Schmitt, a citizen of the United States of America, residing at Denver, in the county of Denver and State of Colorado, have invented a new, original, and ornamental Design for a Vaginal Diaphragm Insertor, of which the following is a specification, reference being had to the accompanying drawing, forming part thereof.

In the drawing:

Fig. 1 is a top plan view of a diaphragm inserter, showing my new design;

Fig. 2 is a side view thereof; and

Fig. 3 is an end view thereof looking from the right in Fig. 2.

I claim:

The ornamental design for a vaginal diaphragm inserter, as shown.

OTTO L. SCHMITT.
